Primary Examiner—Bernard Ansher*Assistant Examiner*—Philip Hyder*Attorney, Agent, or Firm*—Keck, Mahin & Cate**[57]****CLAIM**

The ornamental design for a pair of handles for a crimping tool, as shown and described.

DESCRIPTION

FIG. 1 is a perspective view of a pair of handles for a crimping tool showing our new design;

FIG. 2 is a right side elevational view thereof;

FIG. 3 is a rear end elevational view thereof;

FIG. 4 is a front end elevational thereof;

FIG. 5 is a top plan view thereof;

FIG. 6 is a bottom plan view thereof;

FIG. 7 is a left side elevational view thereof;

FIG. 8 is an exploded perspective view of the pair of handles shown in FIG. 1;

FIG. 9 is a rear end view of the lower handle shown in FIG. 8;

FIG. 10 is a right side view of the handle shown in FIG. 9;

FIG. 11 is a bottom plan view of the handle shown in FIG. 9;

FIG. 12 is a left side view of the handle shown in FIG. 9;

FIG. 13 is a top plan view of the handle shown in FIG. 9;

FIG. 14 is a front end view of the handle shown in FIG. 9;

FIG. 15 is a rear end view of the upper handle shown in FIG. 8;

FIG. 16 is a right side view of the handle shown in FIG. 15;

FIG. 17 is a bottom plan view of the handle shown in FIG. 15;

FIG. 18 is a left side view of the handle shown in FIG. 15;

FIG. 19 is a top plan view of the handle shown in FIG. 15; and,

FIG. 20 is a front end view of the handle shown in FIG. 15. The broken line showing of the crimping tool is for illustrative purposes only and forms no part of the claimed design.
